DESIGN FOR A GOGGLE

Edward M. Splaine, Southbridge, Mass., assignor
to American Optical Company, Southbridge,
Mass., a voluntary association of Massachusetts

Application May 26, 1944, Serial No. 113,762

Term of patent 14 years

(Cl. D57—1)

To all whom it may concern:

Be it known that I, Edward M. Splaine, a citizen of the United States of America, residing at Southbridge, in the county of Worcester and State of Massachusetts, have invented a new, original, and ornamental Design for a Goggle, of which the following is a specification, reference being made to the accompanying drawing, forming a part thereof.

Fig. 1 is a front perspective view of a goggle showing my new design;

Fig. 2 is a bottom plan view partially in perspective; and

Fig. 3 is a side perspective view.

The essential features of my design are shown in full lines and the head-band is shown in a fragmentary condition in Figs. 2 and 3 for convenience of illustration.

I claim:

The ornamental design for a goggle, substantially as shown and described.

EDWARD M. SPLAINE.
